SPRING FLOATED VALVE HEAD

Guy J. Henry, Arlington Heights, Ill.

Application October 13, 1945, Serial No. 622,163

1 Claim. (Cl. 251—46)

1

This invention pertains to improvements in a floating valve seat of the general type illustrated and described in my U. S. Patent No. 1,693,032, dated November 27, 1928.

It is an object of the present invention to provide a valve including a valve seat which is positively acting in both directions, being controlled by a hand operated, screw-type stem, wherein prevention of abrasive action on the valve during seating and minimization of the force required to close and open the same are effected.

Another object is to provide a valve of the above type which insures repeated accurate seating of the valve without damage thereto and resultant leakage.

A more specific object of the invention is to provide a floating valve seat, wherein a spring is embodied in the structural details of floating support of the seat, to the end that chattering and noise in action are avoided, particularly when the valve is employed in a suction line.

Yet another specific object is to provide a spring floated valve of the type described, having a roller bearing, swivel action to minimize friction and facilitate seating and unseating.

The foregoing statements are indicative in a general way of the nature of the invention, but other and more specific objects will be apparent to those skilled in the art upon a full understanding of the construction and operation of the device.

One embodiment of the invention is presented herein for the purpose of exemplification, but it will be appreciated that the invention is susceptible of incorporation in other modified forms coming equally within the scope of the appended claim.

In the drawings,

Fig. 1 is a fragmentary view in side elevation, partially broken away and in vertical transverse section, illustrating a valve seat and associated stem embodying the resilient floated-seat features of the invention;

Fig. 2 is a view in transverse section on a line generally corresponding to line 2—2 of Fig. 1; and

Fig. 3 is a view in vertical section through a valve fitting, illustrating the combination of the improved valve seat of this invention therein.

In my Patent No. 1,693,032 identified above, there are illustrated and described certain improvements in a floating or swiveled valve seat, whereby a substantial minimization of the force required in opening and closing the valve is obtained. The present improvements relate to further improvements in the aforesaid type of valve

2

by elimination of noise and chatter apt to accompany the use of such a lost motion or floating construction in certain connections, for example, in the control of a suction line.

With the valve in the open condition, under such conditions, it is obvious that variations in vacuum-induced flow of fluid will tend to result in some chatter and noise at the seat which it is an object of the present invention to avoid. Further, the improved structure enables a more easy and satisfactory manipulation of the valve, since its initial engagement with the controlled port may be readily detected by feel, notifying the operator that contact has been made and only slight further rotative action is necessary. Furthermore, accuracy of initial seating and repeated reseatings at the same point on the valve is assured, so that a source of possible leakage arising from damage to the valve seat is eliminated.

Referring to the drawings, the reference numeral 10 in Fig. 3 generally designates an L-type valve fitting of conventional construction providing a valve chamber 11, a vertical inlet 12 and a lateral outlet 13. An annular port 14 in line with the inlet projects upwardly in chamber 11, with which port the valve member 15 engages in the operation of the device. Member 15 has an actuating stem 16 threaded externally at 17 for engagement with the housing 10 and is controlled by a hand wheel 18 on the stem externally of the housing, all in conventional manner.

Referring to Figs. 1 and 2, the valve member 15 includes a main body 19 which, on the lower face 20, carries an inlay or insert 21 of relatively soft metal to seal port 14. This insert becomes indented somewhat in repeated engagements with the port 14 to provide an effective seat; and the provisions to be described insure the accuracy of reengagement of said insert seat indentation with the port, whereby misalignment attended by damage to the insert, and resultant leakage, are prevented.

Member 19 is bored or otherwise hollowed centrally on its upper end to provide a circular recess, or chamber, 22 for the floating reception of the lower end 23 of stem 16. Said lower end is of a diameter less than the diameter of recess 22 and carries an annular groove 24 with which the horizontally disposed roller-like pins 25 contact. Said pins are received in the radial openings 26 through the wall of the valve member 19, and are held in retaining engagement with the valve body in groove 24 by a resilient split wire ring 27 encircling the body. A downwardly flared shoulder 28 on stem 16 immediately above

the portion 23 is ultimately engageable with the upper surface of the member 19 and may, if desired, be employed to exert final downward seating thrust when heavy torque is applied to the stem, but a predetermined axial space is provided in any case between shoulder 28 and said surface for a desired vertical lost motion.

Initial downward thrust, upon threading manipulation of stem 16, is transmitted from the stem to the body 19 through the agency of the pins. These have a roller-type engagement in the manner of roller bearings with the upper side of groove 24 to transmit this thrust in a relatively frictionless fashion. Hence, ease of closing manipulation is the result. Also, engagement of the roller pins 25 with the lower side of groove 24 enables a roller-bearing lifting of member 19 when the valve is to be unseated. It should be clearly noted that a certain amount of vertical play of the roller pins 25 in groove 24 permits relative axial motion of the body and stem prior to final seating of the valve. Thereafter relative rotation occurs. Hence, hand actuation of the stem is not impeded by frictional drag of the seat on the valve port, once contact has been made.

Disposed in the recess 22 between the lower end 23 of stem 16 and the bottom of the recess, there is provided a coil compression spring 29 of conical outline, which is under substantial compression in initially installed condition and serves to thrust the body 19 downwardly at all times. This spring thereby damps out and prevents noise and chatter which would otherwise be attendant on movement of the body member 19 relative to the same, as in a vacuum or surging line. It also insures perfect axial alignment of member 19 relative to the stem and port 14 so that it will seat and reseat repeatedly at the same point on the soft metal insert 21. This prevents one factor in the occurrence of leaks past the port, since leaks would tend to arise were the stem indiscriminately engaged with the port so as to damage the existing indentation in the seat insert. With the spring biased structure shown concentricity is insured and misalignment is impossible.

In operation, assuming the valve to be open, initial rotation of the stem 16 causes the head 19 to be translated toward port 14. Prior to engagement with the said port, the spring 29 maintains the lower wall of groove 24 in engagement with the pins 25, in turn urging the pins upwardly against the top of their respective recesses 26, with an appreciable space between the flared shoulder 28 on the stem and the top of the head, and an approximately equal space between the top wall of groove 24 and the top of the pins. Upon initial engagement of head 19 with the port, the spring 29 is compressed somewhat so that the pins fall loose in groove 24, whereupon the stem is freely rotatable relative to the valve head 19, the latter maintaining an angularly fixed engagement with the port. As the stem moves downwardly, taking up the space between the shoulder 28 and the top of the head 19, the pins 25 may roll on the upper wall of groove 24 in the manner of anti-friction bearings; however, the final downward thrust on the valve head is applied by the overhanging flared shoulder, so

that no appreciable shearing stress is applied on pins 25. On the reverse upward movement, these pins also function as bearings during the first few degrees of turn of the stem and thereafter act as articulating elements to transmit lifting effort from the stem to the head 19, after the upward expansion of spring 29 has taken up the lost motion between the stem and head and brought the lower wall of recess 24 into engagement underneath the pins. In neither the seating or unseating movement of the member or head 19 is any substantial shearing stress borne by pins 25, their main purpose being to articulate, swivel or rotatively join the head to the stem and to prevent separation of these members when the valve is unseated. A certain roller bearing action is performed which facilitates initial engagement of the head with the valve port without relative movement therebetween, the pins reducing the friction between the stem and head to this end. However, the main and final seating thrust is applied to head 19 by the flared shoulder 28 integral with the stem.

It will also be perceived that back-seating is performed by said integral flared shoulder, eliminating need for guiding the head in the chamber. The spring 29 insures the maintenance of proper alignment of the head and stem during free movement in the chamber.

What I claim is:

A valve of the type described, comprising a threadedly actuatable, rotatable stem, a valve member telescoped on one end of said stem and movable axially relative thereto, roller bearing means articulating and swiveling said member and stem to engage and disengage the member with a valve port upon rotative actuation of the stem, said stem moving relative to said member following initial engagement of the latter with said port, coacting means on said stem and member engageable to transmit thrust from the former to the latter to finally seat said member against said port following said relative movement, and a compression spring disposed internally of said member in thrust engagement between the same and said end of said stem, whereby to prevent chatter between the stem and member and resiliently maintain the member in predetermined, axially spaced relation to the stem prior to engagement of the member with the port, said roller bearing means limiting the axial spacing of the member relative to the stem and preventing separation thereof under the force of said spring, said stem being rotatable relative to the member when the latter is engaged with the port prior to said final seating.
